UNITED STATES PATENT OFFICE

WILLIAM BROWN, OF NEW HAVEN, CONNECTICUT

DESIGN FOR A SIGNAL LAMP FOR AUTOMOBILES

Application filed April 23, 1931. Serial No. 29,608. Term of patent 3½ years.

To all whom it may concern:

Be it known that I, WILLIAM BROWN, a subject of the King of England, residing at New Haven, in the county of New Haven and State of Connecticut, have invented a new, original, and ornamental Design for Signal Lamp for Automobiles, of which the following is a specification, reference being had to the accompanying drawing, forming part thereof.

In the drawing:—

Fig. 1 is a front elevation of the signal lamp showing my new design;

Fig. 2 is a top plan view of the same; and
Fig. 3 is a side elevational view.

I claim:

The ornamental design for a signal lamp for automobiles, as shown.

WILLIAM BROWN.
